US00D595573S

(12) **United States Design Patent**
Snedden et al.

(10) **Patent No.:** US D595,573 S
(45) **Date of Patent:** ** Jul. 7, 2009

(54) **DEEP LID FOR FOOD CONTAINER**

(75) Inventors: **Craig Richard Snedden**, Culver City, CA (US); **Gandhi Bonergue Sifuentes**, Whittier, CA (US); **Yu Wen Chen**, Shulin (TW)

(73) Assignee: **Direct Pack, Inc.**, Sun Valley, CA (US)

(**) Term: **14 Years**

(21) Appl. No.: **29/326,771**

(22) Filed: **Oct. 24, 2008**

(51) **LOC (9) Cl.** 09-07

(52) **U.S. Cl.** D9/435

(58) **Field of Classification Search** D9/694, D9/573, 560, 554, 529, 504, 503, 502, 456, D9/454, 453, 451, 447, 445, 444, 435, 432, D9/428, 425, 424, 418; D7/629, 396.2, 396.1, D7/300; D3/323; D28/91, 82, 8.1; D26/6, D26/23, 20; 431/291; 222/270, 142.9, 792, 222/266, 226, 212; 217/11; 206/520, 519, 206/508, 505

(57) **CLAIM**

The ornamental design for a deep lid for food container, as shown and described.

DESCRIPTION

FIG. 1 is a top perspective view of a deep lid for food container, showing our new design;

FIG. 2 is a right elevational view thereof;

FIG. 3 is a left elevational view thereof;

FIG. 4 is a front elevational view thereof;

FIG. 5 is a back elevational view thereof;

FIG. 6 is a top plan view thereof; and,

FIG. 7 is a bottom plan view thereof.

The food container tray shown in broken lines is unclaimed environment, and forms no part of the claimed design.

1 Claim, 7 Drawing Sheets
